TOY ENGINE STARTER

A C Boultinghouse, Northridge, Calif., assignor to Wen-Mac Corporation, Los Angeles, Calif., a corporation of California

Original application February 20, 1956, Serial No. 566,721, now Patent No. 2,800,744, dated July 30, 1957. Divided and this application February 28, 1957, Serial No. 643,098

14 Claims. (Cl. 46—78)

My invention relates to a toy power plant assembly for engine driven toy vehicles, incorporating a toy internal combustion engine, and a toy rewind starter.

This application is a division of my copending application, Serial No. 566,721, filed February 20, 1956, for Toy Engine Starter and since matured into Patent No. 2,800,744, and a continuation-in-part of my copending application, Serial No. 484,447, filed January 27, 1955, for Toy Engine Starter, and since abandoned.

In the toy vehicle art such, for example, as toy or scale model airplanes, such toy airplanes have been for the past 19 years provided with miniature or toy internal combustion engines. Such toy airplanes weigh from 2 ounces to 6 ounces and the toy engines are of a weight in the neighborhood of 1 ounce to 5 ounces. They are capable of free flight or captive flight under the skill and manipulation of the operator from the ground.

Such toy aircraft engines are commonly started by a propeller-flipping technique which is difficult to learn and which cannot be learned by many children and some adults, who do not possess the requisite mechanical aptitude. Also there is entailed danger of finger cuts and bruises from repeated contacts with the propeller edge and danger from accidental engagement with the propeller spinner or other rapidly rotating parts.

Many attempts have been made over the years to provide a starter which would overcome the disadvantages and dangers referred to in the preceding paragraph. For example, there have been removable extraneous starter mechanisms known as spinners, egg beaters, mouse traps, etc., and even electric drills and top spinners have been used as attempted makeshift starters.

There has been an urgent need for a toy starter which could be mounted in the fuselage of a toy airplane and which could be operated by anyone, child or adult, without requiring any particular experience or mechanical aptitude.

Until the present invention no practical successful toy rewind starters for toy engines have made their appearance on the market despite the long and pressing need for such a device.

Such a toy starting means must meet limited space, weight and balance factors, must operate successfully in an environment of sticky fuels and in the presence of rather high vibrations caused by toy engine revolutions ranging from 14,000 to 18,000 revolutions per minute. Also, such a toy starting means must be of simple design and function, must be economical to manufacture and assemble. Also, it must be dependable under all conditions and must be rugged to withstand abuse by children. Furthermore, such a toy starter must be removable as a unit for replacement or repair. It must also be capable of consistent quality control notwithstanding close tolerances of one-half to one thousandths of an inch, which tolerances are necessary in engine driven toy constructions.

The present invention has satisfied all of these rigid requirements and applicant has provided a combination

2

of a toy engine and a toy starter having a starter pull cord which extends to the exterior of the fuselage of the toy airplane or the body of the toy vehicle, which may be pulled to turn the toy engine a number of revolutions, which pull cord will, when released, be automatically rewound on the drum ready for a subsequent starting operation. The present invention is always in place and is always ready to perform the starting operation without entailing any particular mechanical aptitude and without danger of finger cuts, bruises or other injuries which result from the propeller flipping technique now in common use.

It is an object of my invention to provide a toy vehicle propelling assembly which includes a toy engine, a propelling means and a toy rewind or recoil starting means in which a starter pull cord extends to the exterior of the vehicle for manual pulling and which, when released, will return to an initial position where it will at all times be ready to perform a subsequent starting operation.

It is an object of my invention to provide a toy propelling assembly which includes a toy engine mounted in the fuselage, a propeller at the forward end and exterior of the fuselage, and a toy rewind starting means positioned within the fuselage and having a pull cord extending through an opening in the fuselage for manipulation by the operator, whereby the toy engine may be turned a number of starting revolutions, and in which the pull cord, upon being released, will be automatically rewound to its initial position ready for subsequent starting operation.

It is an object of my invention to provide a toy power plant assembly for an engine driven toy in which there is a toy recoil starter having a drive element and a winding means operable by a pull cord, the winding means being associated with a plate which is separate from but driven by the winding means. Cooperating between the plate and the drive element is connecting means whereby the drive element may be driven in a forward direction upon pulling the pull cord of the starter.

It is a further object of my invention to provide a toy power plant assembly in which there is a drive element and a winding means or rotation means and in which engagement between the two in a forward direction is accomplished by an inertia responsive means.

It is another object of my invention to provide a power plant assembly comprising a toy engine having a shaft projecting from it, a propeller mounted on the shaft adjacent to the engine and a toy rewind starter positioned between the engine and the propeller, the rewind starter having a pull cord extending to the exterior thereof and having an end in position for manual engagement.

It is a further object of my invention to provide a toy power plant assembly having a toy engine having a shaft projecting therefrom, a propeller secured to the shaft adjacent to the engine and in which there is an auxiliary shaft projecting from the engine in an opposite direction which has a rewind or recoil starter operatively connected to it.

It is an object of my invention to provide a toy starting device for a toy engine having a drive member secured to the shaft, a rotatable member supported concentric to the shaft and drive member, and in which there is inertia means operable between the drive member and the rotatable member whereby the drive member may be driven by the rotatable member in a forward direction.

It is a still further object of my invention to provide a toy power plant assembly having a toy engine with a shaft projecting therefrom and a toy rewind or recoil

starter having its parts supported by and held in proper operating alignment by the shaft and by the engine.

It is also an object of my invention to provide a toy recoil starter for a toy engine which is particularly designed to be of light weight and compact and having unique details of construction which render the starter of simple design, of low production cost, and of economical replacement and repair.

It is an object of my invention to provide such a toy starter in which all of the parts except a single disc-like drive member which is secured to the shaft of a toy engine, remain stationary when the engine is being driven under its own power.

Other objects and advantages of my invention will be made evident in the course of the following detailed description of forms of my invention chosen for the purposes of illustration.

Referring to the accompanying drawings, which are for illustrative purposes only:

Fig. 1 is a perspective view showing a toy airplane having a toy engine, toy starter and propeller assembly mounted therein according to the present invention;

Fig. 2 is an enlarged fragmentary elevational view of the forward end of the fuselage of the toy aircraft showing the toy power assembly of the present invention, parts being broken away and sectioned substantially on line 2-2 of Fig. 3 to disclose the cooperative relationship of the parts;

Fig. 3 is a transverse sectional view showing the details of mounting and manner in which the flexible pull member is brought to the exterior of the fuselage; taken substantially on line 3-3 of Fig. 2;

Fig. 4 is a transverse sectional view showing details of the cam actuated clutch mechanism, taken substantially on line 4-4 of Fig. 2;

Fig. 5 is a transverse sectional view showing details of the rewind spring and its operative connections, taken substantially on line 5-5 of Fig. 2;

Fig. 6 is a fragmentary sectional view showing a modified arrangement in which the starter mechanism is mounted on the opposite side of the crankcase from the main shaft; and

Fig. 7 is a view diagrammatically illustrating a reed type of valve for controlling fuel admission to the engine.

Referring now generally to the drawings, there is illustrated in Fig. 1, a toy or miniature aircraft embodying the features of the present invention, this aircraft comprising a fuselage body 10 having wings 12 and 13 and tail structure 14 at one end of the fuselage. The other end of the fuselage is of hollow construction and provides an engine compartment, this end of the fuselage being streamlined and associated with a forward spinner 15. The power plant as generally indicated at 16 is mounted in the engine compartment and has a driving connection with a propeller 17. Fuel control 18 is brought out through an opening 19 in the fuselage of the engine compartment, while a flexible pull cord 20 is brought out through an opening 21 in the wall of the fuselage, the openings 19 and 21 being positioned rearwardly of the propeller 17.

The combination of the toy vehicle propelling assembly comprising a toy engine, the propelling means and toy rewind starting means will be subsequently described in detail, but is generally of a construction in which the parts are compactly arranged in axial alignment and proper weight balance, the rewind starter means having a one way clutching mechanism for starting the motor or engine in a driving direction by pulling upon the pull cord 20. Placing of the pull cord rearwardly of the propeller provides a safety feature which is of great importance in small aircraft of this type in that the air stream from the propeller acts to blow the pull cord away from the propeller so that it may be rewound without becoming entangled so as to create an

unsafe hazard for the young people who usually fly this type of plane.

Referring to Fig. 2, the toy engine of the power plant 16 has a crankcase 22 formed with a tubular sleeve 23 that provides a bearing support for a projecting main or power shaft 24. At its outer end, the main shaft is fitted with the propeller 17 of conventional construction and is also connected with the spinner 15 which extends over the hub portion of the propeller. The shaft 24 is connected to the pin and connecting rod parts 61 and 62 respectively, as shown in the modification of the invention illustrated in Fig. 6. The toy engine is of a conventional design, the moving parts thereof having low mass for high revolution per minute operation and having relatively low flywheel action for starting.

The conventional power assembly of toy or model aircraft includes a toy engine, a propeller, and streamlined spinner. It is thus customary to start the engine in such prior arrangements by manually flipping the propeller. As pointed out heretofore, many persons are unable to learn the starting technique and are thus deprived of the pleasures and satisfying experiences of maneuvering toy engine driven vehicles; and also, as pointed out heretofore, there is the possibility of injury particularly in the event that the operator's hands are not quickly removed from a path of movement of the propeller, or in the event that the engine should backfire and cause reverse movement of the propeller.

In order to overcome the disadvantages and hazards referred to heretofore, the present invention seeks to eliminate in so far as possible the inherent danger attending the starting of miniature engines of this type, and particularly in the case of toy and model aircraft. Although the starter, which will subsequently be described in further detail, finds particular advantageous use in connection with the engines of models and toy aircraft, the starter is also usable with the engines of model boats, automobiles, etc.

As shown clearly in Fig. 2, the toy or miniature starter of the present invention is positioned between the engine crankcase structure and the propeller, and comprises a two-part housing as generally indicated at 25. One part of the housing is formed by means of a cupped member 26 which is arranged at its central position with an annular flange 27 adapted to surround the tubular sleeve 23 upon which it is retained against movement by means to be hereinafter described. The periphery of the cupped member is formed by an annular flange 28 so that the cupped member has an open end defined by the rim edge 29.

The other part of the housing 25 is formed by a drive plate or drive element 30 centrally provided with a cylindrical hub 31 arranged to have a spline or other suitable interconnection with the shaft for rotation therewith. At its periphery, the drive plate 30 has an axially extending flange 32, the edge of which registers with the rim edge 29 of the cupped member 26.

Mounted within the housing 25 is a rotation member of means which includes a winding means in the form of a winding drum 33 having a tubular hub 34 adapted to be rotatably supported upon the outer surface of the tubular sleeve 23. The inner end of this hub also has its bore slightly enlarged so as to extend over and bear upon the flange 27. The opposite end of the hub is arranged to extend over the hub 31 of the drive member, and extend into an annular groove 35 in the adjacent face of the drive member.

Between the ends of the hub 34, the winding drum has integrally formed with the hub a circumferentially extending flange 36 which is grooved peripherally to form a circumferentially extending groove 37 which is adapted to windingly receive the flexible pull member 20. The inner end of the pull member is knotted and anchored in an opening 39 provided in the flange 36 below the groove 37. The free end of the pull member extends through an

opening 40 provided in the flange 28 and through the opening 21 provided in the fuselage to the exterior of the cupped member 26, where the pull member is provided with an end loop 41 to facilitate manual manipulation by an operator. Inwardly spaced from this looped end, the pull member may be knotted as indicated at 42 so as to limit the rewind movement of the pull member.

On one side of the flange 36, there is positioned within the cupped member 26 a coiled spring 43, one end of this spring being positioned in a slot 44 in the flange 28, so as to anchor this end of the spring to the cupped member, as shown in Fig. 5. The inner end of the coiled spring is anchored in the adjacent wall of the tubular hub 34 by positioning the spring end in a slit 45. The spring 43 is spiraled in a proper direction to actuate the winding drum 33 so as to rewind the pull member automatically.

On the opposite side of the winding drum, there is a projection 33a having flat sides 33b on which is placed a cam plate 46 having a similarly shaped opening 46a. As shown in Fig. 4, the cam plate 46 is provided on diametrically opposite sides with inclined recesses 47, these recesses being formed by an edge 48 and an edge 49 at right angles thereto. The inclined recesses 47, subtend the flange 32 of the drive plate 30, and within each recess there is positioned a disc 50 which is adapted to roll edgewise within the associated recess. As so arranged, when the disc 50 is against the edge 49, the drive plate will be disconnected with respect to the cam plate 46. However, when the pull member 20 is pulled by grasping the end loop 41, the cam plate will be rotated to produce relative rotational movement between said rotation member and said drive element in a locking direction, but due to the inertia of the disc 50 these discs will tend to remain stationary and will assume a wedging position between the associated edge 48 and the adjacent surface of the flange 32. When the discs are in this wedging position, friction or frictional engagement between the disc and the inner surface of the rim 32 and the surface 48 will prevent relative movement between the rotation member and the drive element, so as to interconnect the cam plate and drive plate for unitary movement, thereby causing rotation of the crankshaft to start the engine. The disc or discs 50 taken in connection with the surfaces which they frictionally engage comprises a friction operated means or friction gripping means or element.

As soon as the engine starts, the drive plate movement will overrun, and this action will tend to move the discs 50 to a non-wedging position and permit free operation of the engine. Upon releasing the pull member, the spring 43 acts to return the pull member to the winding drum.

The portion of the pull member which is exterior of the housing 25, upon starting the engine, will be blown away from the propeller by the propeller air stream, thus permitting return of the pull member to the winding drum without danger of becoming entangled in the propeller, when the pull member is released for rewind.

The cupped member 26 is retained against axial and rotary movements on the tubular sleeve 23 by suitable anchoring means (not shown). The drive plate 30 is formed with an annular raised surface 51 which is provided with a roughened or knurled face 52, as shown in Fig. 3, which is arranged to abut the adjacent surface of the propeller hub and form a friction non-slip engagement therewith.

Referring now to Fig. 6, a modified starter construction will be described, which is arranged for mounting on the opposite side of the crankcase from the position shown in Fig. 2. In the modified arrangement, similar parts are indicated by the same numerals as in the form previously described. The modified arrangement is constructed so that it may be mounted upon existing engines, and furnished as an attachment which may be positioned in the place now occupied by the fuel tank 53, Fig. 2.

More specifically, as shown in Fig. 6, the crankcase is provided with a threaded opening 54 which receives the threaded end of a tubular bushing 55, this end of the bushing being provided with a circumferentially extending flange 56 which is adapted to bear against a sealing gasket 57 so as to sealingly mount the bushing in the crankcase opening.

Instead of mounting the starter parts in connection with the main shaft, in the modified arrangement use is made of an auxiliary shaft 58 which is rotatably mounted within the tubular bushing 55. The auxiliary shaft is longitudinally retained in position within the bushing by the drive plate 30 secured at one end by a securing screw 59, and by means of an end flange 60 at the opposite end of the auxiliary shaft.

As shown, the main shaft 24 carries a crank pin 61 which connects with the engine piston rod 62. Provision is made for also driving the auxiliary shaft 58 in concert with the main shaft 24 by the provision of a slot or opening 63 in the end flange 60, this slot or opening being adapted to receive the outer end of the crank pin 61 therein.

The modified starter construction embodies the inherent advantages of the starter construction which is arranged to be mounted between the engine and the propeller, the main difference being that in the modified construction provision is made for mounting the modified construction on the rear side of the crankcase in which position it may be readily used as an attachment for an existing engine, a minimum of changes in the engine construction being required in order to utilize the starter therewith.

One of the problems of providing a starter of the herein described type for engines used in the actuation of toys, resides in the difficulty of making the starter small enough to fit within confined spaces, particularly in the case of toy aircraft, and yet have parts which will operate efficiently, and which instead of merely turning the engine through dead center position will impart a plurality of turns in the desired direction. This latter feature is of particular importance in these model or small engines which are in certain constructions designed to operate with equal facility in reversed directions, that is, in either a forward or reversed direction. For example, reed type valves are conventionally being utilized in these small engines such as disclosed in Fig. 7. As therein shown, the fuel supply conduit 64 is shown as incorporating a partition 65 having an opening 66 therein to permit flow of fuel to the engine. This opening is controlled by a reed 67 in the form of a flat spring or other flexible means which is arranged to open under the suction created in the engine. In this type of engine, there is an absence of the timed admission of fuel as sometimes incorporated in these smaller engines. Thus, a starter of the type described herein is of particular advantage and removes the hazard of starting these engines by flipping the propeller, since a kickback may cause the propeller to go in the opposite direction and thus constitute a dangerous condition, particularly where the engine is being operated by youngsters.

Various modifications may suggest themselves to those skilled in the art without departing from the spirit of my invention, and, hence, I do not wish to be restricted to the specific form or forms shown or uses mentioned, except to the extent indicated in the appended claims.

I claim:

1. In a toy power plant for an engine-driven toy, the combination of: a toy engine having a crankcase, and a crank pin carried by a main shaft, said crank pin having connection with a driving piston rod; a tubular bushing mounted in an opening in said crankcase adjacent the crank pin; a member rotatably supported in said bushing; means at one end of said member engageable with said crank pin so as to drive said member; a drive plate secured to said member for rotation therewith; a rotatable winding drum surrounding said member; a flexible pull member wound on said drum; a rewind spring connected

to said drum; and means actuated by the movement of said drum, upon pulling said pull member, to releasably interconnect said drum and drive plate for unitary movement.

2. In a toy power plant assembly for an engine-driven toy, the combination of: a toy engine having a shaft projecting from said engine, the moving parts of said engine having low mass for high revolutions per minute operation, and, therefore, relatively low flywheel action for starting; a drive element connected to said shaft; starter rotation means between said drive element and said engine and adjacent said drive element and rotatable in forward and rearward directions around the axis of said shaft; one-way overrunning clutch means, said clutch means including a friction operated element frictionally operable between said rotation means and said drive element to establish driving connection therebetween when said rotation means is rotated in forward direction, to rotate said drive element in forward direction; a pull cord wound on said rotation means having one end connected to said rotation means to rotate said rotation means in one of said directions of rotation as said pull cord is unwound from said rotation means; spring means having one end thereof connected to said rotation means so as to be wound as said pull cord is unwound from said rotation means, said spring as it unwinds, rotating said rotation means in the other of said directions; walls forming a guide means for guiding said pull cord relative to said starter rotation means, said pull cord having one end guided by said guide means, said pull cord, upon release after actuation, being rewound onto said rotation means with said end of said pull cord exposed for subsequent starting operations; and means mounted on the engine for connecting said walls forming said guide means and the other end of said spring means to restrain relative movement.

3. In a power plant for a toy propeller driven vehicle, the combination of: a toy engine having a projecting shaft, the moving parts of said engine having low mass for high revolutions per minute operation, and, therefore, relatively low flywheel action for starting; a propeller secured to said engine shaft; a drive element positioned between said propeller and said engine secured to said shaft; starter rotation means positioned between said propeller and said engine adjacent said drive element and rotatable relative to said shaft; one-way overrunning clutch means positioned between said propeller and said engine for connecting said drive element and said rotation means when said rotation means is rotated in forward direction, to rotate said drive element in forward direction; means for rotating said rotation means in forward and rearward directions comprising a pull cord wound on said rotation means having one end connected to said rotation means to rotate the same in one of said directions; guide means positioned adjacent said starter rotation means for guiding said pull cord relatively to said starter rotation means, said pull cord having one end extending from said rotation means through said guide means into a position for manual engagement; spring means positioned between said propeller and said engine having one end connected to said rotation means for rotating said rotation means in the other of said directions, said pull cord, upon release after actuation, being rewound onto said rotation means with said manually engageable end exposed for subsequent starting operations; and means for securing the other end of said spring means relative to said rotation means.

4. In a toy power plant assembly for an engine-driven toy, the combination of: a toy engine of a weight in the neighborhood of one ounce to five ounces and including a crankcase, a sleeve on said crankcase, and shaft means extending from said crankcase through said sleeve and connected for driving engagement with the connecting rod of the engine, the moving parts of said engine having low mass for high revolutions per minute operation, and,

therefore, relatively low flywheel action for starting; and toy starter means supported concentric to said shaft means, said toy starter means having a drive element secured to said shaft means, rotation means on said sleeve adjacent

- 5 to said crankcase rotatable in forward and rearward directions around said shaft, one-way clutch means operable between said rotation means and said drive element, said one-way clutch means including friction means frictionally engageable between said rotation means and said drive element for imparting engine starting rotation from said rotation means to said drive element when said rotation means is rotated in said forward direction, and means for rotating said rotation means in said forward and rearward directions comprising a pull cord wound upon said rotation means so that as said pull cord is unwound from said rotation means it will rotate the same in one of said directions, and a spring connected to said rotation means so that it will be wound as said pull cord is unwound from said rotation means, said spring as it unwinds rotating said rotation means in the other of said directions.

5. In a toy power plant assembly for an engine-driven toy vehicle, the combination of: a toy engine having a shaft; and toy starter means concentric to said shaft, said toy starter means having a drive element secured to said shaft, winding means rotatable around said shaft, a plate drivably carried by said winding means, disc means between said plate and said drive element, operable upon rotation of said winding means, to drivably connect said winding means and said drive element, a housing mounted on said toy engine cooperating with said drive element to enclose the other of said toy starter means parts, a starter pull cord connected to said winding means for rotating same, and rewind means for rotating said winding means to its initial position and for returning said pull cord to its initial position.

6. In a toy power plant assembly for a toy propeller driven vehicle, the combination of: a toy engine having a power delivery shaft extending from said toy engine in one direction and an auxiliary shaft extending from said engine in the opposite direction, both of said shafts being operatively connected with the connecting rod of said engine, the moving parts of said engine having low mass for high revolutions per minute operation, and, therefore, relatively low flywheel action for starting; a propeller secured to said power delivery shaft; a drive element secured to said auxiliary shaft; power rotation means rotatable relative to said auxiliary shaft; one-way overrunning clutch means for connecting said drive element and said rotation means when said rotation means is rotated in a forward direction, to rotate said drive element in forward direction; means for rotating said rotation means in forward and rearward directions comprising a pull cord wound on said rotation means, having one end connected to said rotation means to rotate the same in one of said directions; guide means positioned adjacent said starter rotation means for guiding said pull cord relatively to said starter rotation means, said pull cord having one end extending from said rotation means through said guide means into a position for manual engagement; spring means connected to said rotation means for rotating said rotation means in the other of said directions, said pull cord, upon release after actuation, being rewound onto said rotation means with said manually engageable end exposed for subsequent starting operations; and means for securing the other end of said spring relative to said rotation means.

7. In a toy power plant assembly for an engine-driven toy, the combination of: a toy engine having a drive shaft projecting therefrom; toy propelling means secured to said shaft and rotatable in axial alignment therewith; and toy recoil starter means surrounding said shaft between said propelling means and said engine including, starter rotation means adjacent said toy engine and rotatable in forward and rearward directions around the

axis of said shaft, support means secured to said engine for rotatably supporting said starter rotation means, a drive element secured to said shaft outwardly of said starter rotation means, one way overrunning clutch means for connecting said drive element and said rotation means when said rotation means is rotated in a forward direction, to rotate said drive element in a forward direction, a pull cord wound on said rotation means having one end connected to said rotation means to rotate said rotation means in one of said directions of rotation as said pull cord is unwound from said rotation means, and spring means positioned between said engine and said drive element having one end thereof connected to said rotation means so as to be wound as said pull cord is unwound from said rotation means, said spring means as it unwinds rotating said rotation means in the other of said directions.

8. In a toy power plant assembly for an engine-driven toy, the combination of: a toy engine of a weight in the neighborhood of one ounce to five ounces and having a shaft projecting therefrom; and recoil toy starter means surrounding said shaft including starter rotation means adjacent said toy engine and rotatable in forward and rearward directions around the axis of said shaft, support means secured to said engine for rotatably supporting said starter rotation means, a drive element secured to said shaft outwardly of said starter rotation means with said starter rotation means between said drive element and said engine, one way overrunning clutch means including friction means operable by frictional engagement to drivably connect said drive element and said rotation means when said rotation means is rotated in a forward direction, to rotate said drive element in forward direction and operable by friction upon relative movement of said rotation means and said drive element in the opposite direction to release the connection between said rotation means and said drive element, a pull cord wound on said rotation means having one end connected to said rotation means to rotate said rotation means in one of said directions of rotation as said pull cord is unwound from said rotation means, and spring means positioned between said engine and said drive element having one end thereof connected to said rotation means so as to be wound as said pull cord is unwound from said rotation means, said spring as it unwinds rotating said rotation means in the other of said directions.

9. In a toy power plant assembly for an engine-driven toy, the combination of: a toy engine of a weight in the neighborhood of one ounce to five ounces and having a shaft projecting therefrom; and recoil toy starter means surrounding said shaft including, starter rotation means adjacent said toy engine and rotatable in forward and rearward directions around the axis of said shaft, support means secured to said engine for rotatably supporting said starter rotation means, a drive element secured to said shaft outwardly of said starter rotation means with said starter rotation means between said drive element and said engine, one way overrunning clutch means, said clutch means including a friction operated element frictionally operable between said rotation means and said drive element to establish driving connection therebetween when said rotation means is rotated in a forward direction, to rotate said drive element in forward direction, a pull cord wound on said rotation means having one end connected to said rotation means to rotate said rotation means in one of said directions of rotation as said pull cord is unwound from said rotation means, and spring means positioned between said engine and said starter rotation means having one end thereof connected to said rotation means so as to be wound as said pull cord is unwound from said rotation means, said spring as it unwinds rotating said rotation means in the other of said directions.

10. In a toy power plant assembly for an engine-driven toy, the combination of: a toy engine having a shaft projecting therefrom; propelling means secured to said shaft; a drive element positioned between said propelling means and said engine secured to said shaft; starter rotation means positioned between said propelling means and said engine adjacent said drive element and rotatable relative to said shaft; one way overrunning clutch means positioned between said propelling means and said engine for connecting said drive element and said rotation means when said rotation means is rotated in a forward direction, to rotate said drive element in a forward direction; and means for rotating said rotation means in forward and rearward directions comprising a pull cord wound on said rotation means having one end connected to said rotation means to rotate the same in one of said directions, said pull cord having one end extending from said rotation means into a position for manual engagement, and spring means positioned between said propelling means and said engine connected to said rotation means for rotating said rotation means in the other of said directions, said pull cord, upon release after actuation, being rewound onto said rotation means with said manually engageable end exposed for subsequent starting operations.

11. In a toy power plant assembly for an engine-driven toy, the combination of: a toy engine of a weight in the neighborhood of one ounce to five ounces and having a projecting shaft; a non-rotatable sleeve supported as an extension from the crankcase of said engine and surrounding a portion of said shaft; rotation means supported on said sleeve for rotation in forward and rearward directions around the axis of said shaft; a spring having one of its ends connected to said rotation means so that said spring will be wound when said rotation member is rotated in one of said directions and in unwinding will rotate said rotation means in the other of said directions; a drive element connected to said shaft adjacent the end of said sleeve; and one way clutch means between said rotation means and said drive element including a frictional engaging means for connecting said rotation means and said drive element so that relative forward rotation of said rotation means will cause said frictional engaging means to frictionally drive said drive element so as to rotate said shaft in forward, engine-starting direction, said clutch means being released when said drive element rotates in forward direction relative to said rotation means.

12. In a lightweight toy engine starting device for a toy engine of a weight in the neighborhood of one ounce to five ounces and having shaft means projecting therefrom, the moving parts of said engine having low mass for high revolutions per minute operation and therefore relatively low flywheel action for starting, the combination of: starter rotation means surrounding said shaft means and rotatable in forward and rearward directions around the axis of said shaft means; spring means having one end connected to said rotation means so as to be wound when said starter rotation means is rotated in one direction; and one-way clutch means positioned outwardly of said starter rotation means operable between said starter rotation means and said shaft means, said one-way clutch means including friction means operable by relative movement between said starter rotation means and said shaft means for establishing driving frictional connection between said starter rotation means and said shaft means and operable by friction when said shaft means moves in a forward direction relative to said starter rotation means, to release driving engagement between said starter rotation means and said shaft means.

13. In a lightweight toy engine starting device for a toy engine having shaft means projecting therefrom, the moving parts of said engine having low mass for high revolutions per minute operation and therefore relatively

low flywheel action for starting, the combination of: starter rotation means rotatable around said shaft means in forward and rearward directions; a housing non-rotatably secured to the crankcase of said engine and surrounding said shaft means between the starter rotation means and engine; a spring positioned in said housing having one end secured to said housing and the other end secured to said starter rotation means; a drive element connected to said shaft means outside and adjacent said starter rotation means; and one-way clutch means operable between said starter rotation means and said drive element, said one-way clutch means including engageable surfaces on said drive element and said starter rotation means, and wedge element means movable by relative movement between said rotation means and said drive element, into engagement with said surfaces for connecting said rotation means and said drive element so that forward rotation of said rotation means will be transmitted to said drive element so as to rotate said shaft means in a forward direction, and being movable to release said starter rotation means and said drive element when said drive element rotates in a forward direction relative to said starter rotation means.

14. In a lightweight toy engine starting device for a toy engine of a weight in the neighborhood of one ounce to five ounces having a shaft projecting therefrom, the moving parts of said engine having low mass for high revolutions per minute operations and therefore relatively low flywheel action for starting, the combination of: rotation means surrounding said shaft and rotatable in forward and rearward directions; a spring having one end secured stationary relative to said engine and having the other end connected to said rotation means, said spring being wound when said rotation means is rotated in one direction and unwound when said rotation means is rotated in the other direction; drive element means secured to said shaft outwardly of said rotation means with

5 said rotation means and said spring positioned between said element means and said engine; a one-way overrunning clutch having a friction gripping element supported at least by one of said means and operable upon relative movement, between said rotation means and said drive element means, in a locking direction, to cause said friction gripping element to, by frictional engagement, lock said rotation means and said drive element means to rotate together; and a pull cord wound on said rotation means, for rotating said rotation means in a direction to wind said spring.
